UNITED STATES PATENT OFFICE

ALBERT NEUMANN, OF COSWIG, GERMANY

STOP-CYLINDER PRINTING MACHINE WITH SHEET DELIVERY AT THE FRONT

Application filed January 23, 1928, Serial No. 248,877, and in Germany January 27, 1927.

Stop-cylinder printing-machines with sheet delivery at the front in which the grippers of the impression cylinder are situated in proximity to the line of contact between the impression cylinder and the platen have become known.

In one of the machines of this type the sheet is laid from above on the grippers of the impression cylinder and conducted, during the rotation prior to the impression, to the grippers of an intermediate cylinder, these grippers delivering the sheet to a second gripper system, arranged on the impression cylinder and running after said first mentioned gripper-system, and bringing the sheet close to the line of impression, when the impression-cylinder is in the stopped position. In this form of construction the sheet is transferred twice to other grippers, wherefrom differences as regards fit may result.

According to another form of construction the laying-on table is brought directly above the plate and the sheet to be printed is laid on the impression cylinder from below. As however the sheet-deliverer is situated above the laying-on table, the laying on of the sheet is rather difficult as only a comparatively small space is left between the laying on table and the sheet-deliverer. The sheet can be observed only from the side and a further inconvenience is, that the laying on table is darkened by the sheet-deliverer above the same.

According to the invention the sheet to be printed is laid during the rotation of the impression cylinder from above against the marks of the laying-on table. As soon as the impression-cylinder has stopped and the previously printed sheet, the printed side turned up the beginning of the printing moving first, has rolled off towards the sheet-delivering-device, the preliminary grippers, oscillatably mounted on the axle of the cylinder, grip the laid-on sheet and convey the same to the impression cylinder-grippers. When these latter grippers have gripped the sheet, the preliminary grippers open and release the sheet. The impression-cylinder conveys the sheet to the printing and rolls it towards the sheet delivering device. For the preliminary

grippers air suction nozzles might be substituted which suck on the sheet from the laying-on table and convey the same to the impression cylinder-grippers. After these grippers have closed, the suckers release the sheet and oscillate back. In order that the oscillatable arms, pivotally mounted on the axle of the impression cylinder, carry out their oscillating movement uniformly, i. e. are not turned the one towards the other, they are driven from a continuously revolving shaft, mounted on the outer side of the impression cylinder by means of toothed segments or the like.

The advantage of this invention is, that the sheet can be laid on easily and accurately and that it can be brought by the preliminary grippers or suckers directly to the impression cylinder-grippers so that no differences of fit can occur.

An embodiment of the invention is illustrated, by way of example, in the accompanying drawing in which:

Figs. 1 and 2 show the mechanism in two different working positions.

Fig. 3 is an assembly view of the invention applied to a printing press, indicating the cooperation of the several printing and feeding elements.

Fig. 3^a is a detail view to be associated with Fig. 3, to show the cams for working the sectors and locating or justifying devices.

Figs. 4 and 5 show portions of the preliminary gripper system in the positions occupied during transfer of the sheet to the impression cylinder grippers.

The impression-cylinder *a* is shown in the position of rest. Its motion is derived from the shaft 1, which is used to drive all the components of the machine. During its motion the impression cylinder remains in toothed engagement with the rack of the carriage 4 which is reciprocated from the crank 2 through the intermediary of the gear wheel 3. The impression cylinder *a*, during the rearward travel of the carriage 4, is held by the forked member 7 which engages a roller 8 on the impression cylinder and which is given an intermittent motion through the connecting link 6 from the usual double eccentric 5 carried by the shaft 1. As the

crank 2 turns through the dotted circle shown, its connecting rod 2^a pulls the gear wheel 3 back and forth from a position to the right to the dotted line position shown at the left in Fig. 3, and back again. During this, the gear wheel 3 moves on the fixed rack 3^a, and thereby advances the chase or type carriage 4 from the position shown in full lines to that shown in dotted lines, and back again: the travel of the carriage 4 being twice that of the gear 3.

The carriage 4 has a rack 4^a on its upper surface, to mesh with gear teeth on the printing cylinder *a*: these teeth, however, are omitted for a portion of the cylinder periphery so that the carriage 4 may pass the cylinder without operation thereon when this part of the cylinder is presented to the carriage 4. When the carriage 4 travels from the dotted left hand position shown in Fig. 3 toward the right, the gear teeth of the cylinder mesh with the rack teeth of carriage 4 and the cylinder is operated for the printing. During the return movement of the carriage 4 from the right hand position back into the dotted left hand position, however, the mutilated portion of the cylinder *a* is presented, and the roller 8 has just been engaged, at the beginning of this leftward movement, with the socket in the upper end of lever 7: the cylinder *a* is thus held against movement. The presentation of the lever 7 for this purpose is effected by the cooperation of the double cam 5 with the rollers on the connecting rod 6, whereby the connecting rod 6 is held in the central position, with the lever 7 upright as shown in Fig. 3. During the leftward movement of the carriage 4, the double cam 5 presents its concentric portions to the rollers on connecting rod 6, so that the lever 7 remains in the position shown. When the carriage 4 reaches the left hand position, the double cam 5 presses its raised portion against the rollers on the connecting rod 6, so that the lever 7 is moved to operate through the roller 8 to give a small rotation to the cylinder *a*, so that as the carriage 4 begins its movement toward the right, the rack 4^a thereof engages the teeth on the cylinder *a* and causes a rotation of the latter for a complete revolution, and until the carriage 4 has reached its right hand position. At this point, the double cam 5 again operates the lever 7 so that the lever is again ready to receive the roller 8, and does so receive this roller and move the cylinder definitely to the position shown in Fig. 3 at the beginning of the next leftward movement of the carriage 4. This operation continues in the same manner. This portion of the construction is well known and is used in all half cylinder high speed printing presses.

On the stationary laying-on table *b* the sheet *d* to be printed is positioned against the locating or justifying devices *c*.

The timed opening and closing of these locating devices *c* is effected by means of a connecting rod-and-link system 41, 42, 43, 44, 45, of which the roller 46 is held by a tension spring 47 against an eccentric 48 which is keyed to the shaft 1 (best shown in Fig. 3).

The swinging arms *g* are loosely mounted on the spindle of the impression roller *a* and are controlled by a pair of toothed segments *h* which engage with a further pair of toothed segments *i* mounted on a shaft *k*. This shaft *k* is operated through the rod 9 and the lever 10 carrying the roller 11 which travels in a continuous guideway 12 secured to the shaft 1. The swinging arms *g* carry on radially adjustable members *z* a rotatable spindle or tube *f*, to which are secured the preliminary grippers *e*. The spindle *f* is rotated by means of roller carrying arms 13 in cooperation with springs 14 which tend to press the preliminary grippers *e* against a series of contacts 15 rigidly secured to the members *z*. The roller arms 13 derive their motion from the sectors 16 which are freely mounted on the spindle supports of the cylinder and are furnished with oblique faces 17 and 18 above and below on which the rollers of levers 13 run. The sectors 16 are controlled by the rod 19 and link 20, which latter is keyed to the through shaft 21. This is oscillated by means of the link system 22, 23, 24, which is operated by means of a roller engaging in a continuous guide groove 25 secured to the shaft 1. For the sake of clearness this guide groove is shown separately in Fig. 3. The radially adjustable members *z* on the swinging arms *g* are provided on their inner faces with rollers 26 which are urged by springs 27 against the inner guide surfaces of the sector arms 16. These inner surfaces are concentric with the cylinder *a* except for a short swell at their lower ends. The preliminary gripper system *g*, *z*, *f*, *e*, 15 thus swings for the greater part concentrically with the cylinder *a* and at a determined distance therefrom. However, at the position in which the sheet is to be transferred to the impression cylinder grippers, the swell 28 causes the preliminary gripping system to approach the cylinder.

The impression cylinder grippers *l* are operated in known manner through the medium of a lever 29 carrying a roller which is held by a spring 30 against an eccentric 31 freely mounted on the axis of the cylinder. A simple method of effecting the required displacement of the eccentric 31 is illustrated in Fig. 3 where the system comprising link 32, bell crank 33, spring 34 and cam surface 35 carried by the carriage 4, is provided. A stop 36' serves to retain the eccentric 31 in its position of rest. It is obvious that other known arrangements for effecting such a

motion may be substituted for the simple system here described.

The printed sheet is guided from the impression cylinder *a*, which is rotating in the direction indicated by the arrow in Fig. 3, in known manner by guide tongues *m* mounted on a spindle. During the passage of the reciprocating preliminary gripper system the tongues *m* must be lifted in timed relation thereto. This is effected through the raising of the roller-carrying lever 36 from the stop 37 consequent to the roller engaging with a segmental member 38 carried by the outer end of the toothed sector *i*. A short link 39 transmits the motion to the tongues *m*. The sheet passes in known manner between the rollers 40 and *n* which guide it to the delivery table.

The co-operation of the described components, in accordance with the invention, is as follows:

In Fig. 3 the carriage 4 is shown in its extreme position to the right; it commences its return travel to the left, during which no printing occurs and the impression cylinder *a* also remains in its rest position. The preliminary gripper system, which is in its uppermost position adjacent the preliminary locating devices *c*, has gripped the edge of the sheet *d* in its grippers *e*. Through the action of the eccentric 48 the locating devices *c* are now lifted. The swinging arms *g* together with the preliminary gripper system begin their downward travel, due to the contour of the guide groove 12 carried by the shaft 1. After this system has passed, the ejecting guide tongues *m* sink into their operative position consequent to the roller 36 running off the segmental member 38. Also the preliminary locating devices *c* are brought into their active position after the passage of the rear-end of the sheet through the corresponding co-operation of the eccentric 48 and the rod- and link-system, so that the next sheet can be laid on immediately. Fig. 4 shows the preliminary gripper system and sheet during the downward travel, up to the point where the roller 26 engages with the corresponding swell 28 on the inner guide surface of the sectors 16. In this manner the members *z* are urged towards the centre of the cylinder; the edge of the sheet is thereby pressed against the outer surface of the cylinder (as shown in full lines in Fig. 4). In this position the roller of the lever 13 of the preliminary gripper system is practically contacting with the projection 18 on the sector 16, without engaging it however. The cylinder grippers *l* now close as during the return motion of the carriage 4. The eccentric 31 controlling the grippers is operated through the cam surface 35. Then, in consequence of a sharp reentrant *P* in the rotating guide groove 25 (Fig. 3), a sudden jerky upward motion is given to the sectors 16 where-

by the preliminary grippers *e* are opened by the action of the projection 18. The forward edge of the sheet is now held by cylinder grippers *l* only. Directly after the opening of the grippers *e* the roller 11 traverses the portion *R* of the guide groove 12, so that the swinging arms *g* execute a small forward motion. In this manner the opened preliminary grippers *e* are removed from the edge of the sheet, so that the latter is completely freed therefrom. Simultaneously the preliminary grippers are again closed by the roller of lever 24 engaging the portion *Q* of the guide groove 25, which causes a rotation of the sectors 16 and disengages the projection 18 from the roller of lever 13. At the same time the rollers 26 leave the swells 28 on the inner surfaces of sectors 16, whereby the members *z* together with the preliminary grippers *e* are displaced outwardly relatively to the cylinder, so as not to hinder the passage of the sheet to printing position (Fig. 5). During the operations described the carriage 4 has reached the end of its return travel (indicated in dotted lines, Fig. 3) and commences the printing stroke (to the right, Fig. 3). The impression cylinder, controlled by the motion of the forked member 7, commences to turn in the direction of the arrow and comes into toothed engagement with the carriage 4; printing then occurs. During printing the preliminary gripper system again swings upwards, but so slowly that the ejector guide tongues *m* do not need to be raised until after the printed sheet has been ejected. During this motion the closed preliminary grippers are spaced from the surface of the impression cylinder by the same amount as during their downward motion. After the tongues *m* have been lifted the preliminary gripper system passes on to the locating devices *c* where it remains stationary. During the last portion of the upward travel, the preliminary grippers are re-opened through the displacement of the lever 13 due to its roller encountering the upper projections 17 of the pair of sectors 16. In the meantime the next sheet has been placed in position against the locating devices *c*, and directly after the preliminary gripper system has reached its upper position the grippers are closed by the release of the rollers carried by lever 13 from projections 17 on the sectors 16 consequent to a short upward motion of the sectors due to the contour of the guide groove 25 at the position *S*. Meanwhile the carriage 4 has reached the end of its printing stroke (shown in full lines in Fig. 3) and the working cycle as described is started afresh.

Having now particularly described and ascertained the nature of my said invention and in what manner the same is to be performed, I declare that what I claim is:

1. A stop-cylinder printing machine with sheet delivery at the front, in which the im-

70 by the preliminary grippers *e* are opened by the action of the projection 18. The forward edge of the sheet is now held by cylinder grippers *l* only. Directly after the opening of the grippers *e* the roller 11 traverses the portion *R* of the guide groove 12, so that the swinging arms *g* execute a small forward motion. In this manner the opened preliminary grippers *e* are removed from the edge of the sheet, so that the latter is completely freed therefrom. Simultaneously the preliminary grippers are again closed by the roller of lever 24 engaging the portion *Q* of the guide groove 25, which causes a rotation of the sectors 16 and disengages the projection 18 from the roller of lever 13. At the same time the rollers 26 leave the swells 28 on the inner surfaces of sectors 16, whereby the members *z* together with the preliminary grippers *e* are displaced outwardly relatively to the cylinder, so as not to hinder the passage of the sheet to printing position (Fig. 5). During the operations described the carriage 4 has reached the end of its return travel (indicated in dotted lines, Fig. 3) and commences the printing stroke (to the right, Fig. 3). The impression cylinder, controlled by the motion of the forked member 7, commences to turn in the direction of the arrow and comes into toothed engagement with the carriage 4; printing then occurs. During printing the preliminary gripper system again swings upwards, but so slowly that the ejector guide tongues *m* do not need to be raised until after the printed sheet has been ejected. During this motion the closed preliminary grippers are spaced from the surface of the impression cylinder by the same amount as during their downward motion. After the tongues *m* have been lifted the preliminary gripper system passes on to the locating devices *c* where it remains stationary. During the last portion of the upward travel, the preliminary grippers are re-opened through the displacement of the lever 13 due to its roller encountering the upper projections 17 of the pair of sectors 16. In the meantime the next sheet has been placed in position against the locating devices *c*, and directly after the preliminary gripper system has reached its upper position the grippers are closed by the release of the rollers carried by lever 13 from projections 17 on the sectors 16 consequent to a short upward motion of the sectors due to the contour of the guide groove 25 at the position *S*. Meanwhile the carriage 4 has reached the end of its printing stroke (shown in full lines in Fig. 3) and the working cycle as described is started afresh.

Having now particularly described and ascertained the nature of my said invention and in what manner the same is to be performed, I declare that what I claim is:

1. A stop-cylinder printing machine with sheet delivery at the front, in which the im-

5
pression cylinder grippers are, during the stop of the impression cylinder, in proximity to the bed, comprising in combination with the laying on table and with the gripper on the impression cylinder, oscillatable preliminary grippers for conveying during the stopping of the impression cylinder the sheet to be printed from the laying on table to the impression cylinder-grippers.

- 10 2. A stop-cylinder printing machine with sheet delivery at the front, in which the impression cylinder grippers are, during the stop of the impression cylinder, in proximity to the bed, comprising in combination with
15 the laying on table and with the grippers on the impression cylinder, preliminary grippers oscillatably mounted on the axis of the impression cylinder for conveying during the stopping of the impression cylinder the sheet
20 to be printed from the laying on table to the impression cylinder-grippers.

3. A stop-cylinder printing machine with sheet delivery at the front, in which the impression cylinder grippers are, during the stop of the impression cylinder, in proximity to the bed, comprising in combination with the laying on table and with the grippers on the impression cylinder, oscillatable preliminary grippers for conveying during the stopping of the impression cylinder the sheet to be printed from the laying on table to the impression cylinder-grippers, toothed segments one on each oscillatably preliminary gripper, a shaft rotatably journaled at the outer side of said impression cylinder, and toothed segments on said shaft meshing with said toothed segments on said oscillatable preliminary grippers.

In testimony whereof I have affixed my signature.

ALBERT NEUMANN.
